TILTABLE SUPPORT

Charles J. Schmitt, Chicago, Ill., assignor to
 Lovejoy Flexible Coupling Co., Chicago, Ill., a
 corporation of Illinois

Application December 29, 1950, Serial No. 203,357

4 Claims. (Cl. 248—23)

1

This invention relates to supports for electric motors and the like which are manually tiltable by rotation of a screw to vary the inclination of the supporting surface.

The general object is to provide a support of the above character which is substantially simpler in construction than prior similar supports, and which enables a finer adjustment of the supported surface to be obtained.

A more detailed object is to connect the tiltable support to its base through the medium of a differentially acting screw.

Other objects and advantages of the invention will become apparent from the following detailed description taken in connection with the accompanying drawings, in which:

Figure 1 is a fragmentary side elevational view showing an electric motor mounted on a tiltable support embodying the novel features of the present invention with a part of the support being broken away and shown in section.

Fig. 2 is a longitudinal sectional view taken along the line 2—2 of Fig. 1.

Figs. 3 and 4 are fragmentary views taken respectively along the lines 3—3 and 4—4 of Fig. 2.

As shown in the illustrative embodiment, the improved support is especially useful in mounting an electric motor 10 on a base 11 for tilting of the motor shaft 12 in an arc 13 by turning a hand crank 14 in a corresponding direction. The base is generally rectangular and has a flat bottom surface and a lug 15 rigid with and upstanding from the base center. The lug is formed with a transverse hole 16 through which extends a pin 17 held against longitudinal shifting as by a set screw 18 projecting into a circumferentially extending slot in the pin.

The pin 17 defines the axis of tilting of the motor whose base 19 is secured to a member 20 pivotally supported intermediate its ends on the pin 17. Herein, the member comprises two rigid bars 21 having flattened surfaces 22 at opposite ends against which the four corners of the motor base 19 may be clamped by bolts 23. Rigid with and depending from each bar midway between its ends is an arm 24 whose lower end is apertured to receive one end of the pivot pin 17. One arm is secured to the pin by a set screw 25 while the other is slidable on the other end of the pin to permit lateral adjustment of one bar according to the width of the base on the motor to be supported.

Upstanding from one end of the base 11 and spaced along the latter from the pivot 17 is a lug 26 having a notch 27 at its upper end spanned by a cross-pin 28 which is disposed somewhat

above the level of the pivot 17 and extends parallel to the latter. Within the slot, the pin 28 is formed with a hole 29 of a diameter substantially equal to the width of the slot and internally threaded to receive and mate with the corresponding threads 30 on the outer end portion of a screw shaft 31. Thus, the cross-pin 28 constitutes a tiltable nut journaled on the base 11. A disk 32 fast on the outer end of this shaft carries the crank 14 which may be turned to advance the shaft endwise through the tiltable nut 28 which is centered relative to the lug by engagement of the sides of the screw with the walls of the notch 27.

In accordance with the present invention, the endwise motion of the screw shaft 31 is communicated to the tiltable support 20 by a threaded connection related in a novel manner to the screw and nut above described. Herein, the connection comprises a thread 33 cut on the other end portion of the shaft 31 and mating with the interior of a hole 34 which extends diametrically through a nut 35. The latter comprises a rod spanning the depending arms 24 on the member 20 with its opposite ends journaled in the arms and spaced above the pivot 17. The threads 30 and 33 are of different pitches respectively having 16 and 28 turns per inch in the present instance, both threads extending helically around the shaft 31 in the same direction.

By virtue of the difference in the pitch of the two threads, two given points on the two threads will advance at different rates relative to their mating nuts during rotation of the shaft 31 in either direction. Because of this difference and the fact that the nut 28 is journaled on the base 11, the other nut 35 will move back and forth as the shaft is turned in opposite directions. The member 20 on which the nut 35 is carried may thus be tilted in either direction from the horizontal position shown in Fig. 2 in which the shaft is disposed horizontally by virtue of the location of the nuts at the same level above the bottom of the base 21. As an incident to such tilting, the shaft 31 also tilts as shown in Fig. 1 but to a lesser degree. This is permitted by virtue of the loose mounting of the nuts 28 and 35 in the lug 26 and the arms 24.

By employing the threaded connection between the shaft 31 and the supporting member 20, the overall construction is greatly simplified since only boring and threading operations are required. Moreover, there is no danger of binding between the relatively moving parts and in addition, the desired fineness of adjustment may be achieved simply by selecting the proper differ-

ence in the pitches of the two threads 30 and 33.

I claim as my invention:

1. A tilting support comprising a base, a member having an upper supporting surface and a depending arm intermediate its ends, a pin pivotally connecting said base and the lower end of said arm for swinging of the member about an axis paralleling the bottom of the base and said surface, a nut paralleling said pin and journaled in said arm between said surface and the pin, said nut having a hole extending diametrically therethrough with an internal thread of a predetermined pitch, a second nut mounted on and spaced along said base from said first nut and having a horizontally extending hole aligned with said first hole, said second hole having an internal thread of a pitch differing from that of said first hole, a screw shaft extending through said two holes and having opposite threaded end portions mating with the threads of the respective holes, and a means on one end of said shaft by which the shaft may be turned to tilt said member relative to said base and about said axis.

2. A tiltable support comprising a base, a horizontal pivot pin mounted thereon, two bars having upper supporting surfaces and mounted on opposite end portions of said pin to swing about the axis thereof, one of said bars being adjustable along the axis of said pin, a screw shaft disposed above and extending transversely of said axis, means rotatably connecting said shaft to said bars above said axis for rocking of the bars in accordance with the endwise movement of the shaft, a nut threaded onto said shaft at a point spaced from said connection, means on said base supporting said nut to rock about an axis paralleling said pivotal axis, and walls rigid with said base and engageable with said shaft on opposite sides thereof to position the shaft laterally.

3. In a tilting support, the combination of, a base member, a supporting member mounted on said base member for swinging about an axis extending across the base member, a screw shaft 5 extending transversely of said axis, threads of different pitch formed along opposite end portions of said shaft, two nuts, one threaded onto each of said shaft end portions, a connection between one of said nuts and said base member, and a second connection between the other of said nuts and said supporting member, the connection between at least one of said nuts and the associated member including relatively movable parts connected respectively to said one nut and said associated member to permit relative turning between the two.

4. A tilting support comprising a base, a supporting member pivotally mounted on said base to swing about a first axis extending across the base, a screw shaft extending transversely of said axis, threads of different pitch formed along opposite end portions of said shaft, a nut threaded onto one of said shaft end portions and connected to said member for turning relative thereto, and 20 a second nut threaded on the opposite end portion of said shaft and connected to said base for turning relative to the same, said nuts turning about axes paralleling said first axis.

CHARLES J. SCHMITT.
